UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed April 7, 1919, Serial No. 288,133. Renewed November 6, 1926.

My invention relates to mining apparatus.

It has for its object to provide improved mining apparatus especially adapted to use in entry driving. A further object of my invention is to provide an improved entry driving apparatus adapted to advance an entry rapidly and provided with improved cutting and feeding means adapted to produce an entry of the desired width with a minimum of cutting. A still further object of my invention is to provide an improved entry cutting apparatus adapted to produce an improved entry having the desired flat bottom and arched roof, and also having provision for removing any obstructions such as sulphur, black jack, or the like. These and other objects and advantages of my improved construction will, however, herein-after more fully appear.

In the accompanying drawings, I have shown for purposes of illustration one embodiment which my invention may assume in practice.

In these drawings,—

Fig. 1 is a plan view, partially in section, of a mining apparatus constructed in accordance with my improvement, the same being shown in position in an entry.

Fig. 2 is a side elevation of the same, showing the rear section in two positions.

Fig. 3 is a front elevation showing the cutting mechanism.

Fig. 4 is a transverse sectional view taken substantially on line 4—4 of Fig. 2, the conveyor mechanism being omitted to facilitate illustration.

Fig. 5 is a detailed sectional view taken on line 5—5 of Fig. 4.

Fig. 6 is a detailed sectional view taken on line 6—6 of Fig. 4.

In this illustrative construction, it will be observed that I have shown an apparatus including a cutter carrying section 1 and an anchoring section 2, the same being connected by feed screws 3, as herein-after described, so that they may be successively advanced as the entry is driven, the cuttings being removed and preferably delivered to a car by a conveyor 4 of any suitable construction, herein extending to a point beneath the front end of the section 1 and rearward and upward over the top of the section 2.

Of these sections, the cutter carrying section 1 herein also carries the cutter driving and feed operating mechanism. Referring

more particularly to Fig. 3, a substantially elliptical cutter carrying element, herein a bar 5, is supported substantially vertically and against the face across the front of the machine, the same herein being provided with the usual rounded ends and with curved or arcuate upper surface 6 and a straight or horizontal lower surface 7. Around this cutter bar and along these surfaces moves a cutter chain 8 having cutter bits 9 disposed in the usual relation thereon but projected forward in such a manner that they will cut only on the front side of the chain as the latter is moved around the bar. Here it will also be noted that in suitable spaced relation on the chain, I have provided rearwardly extending scrapers 10, for a purpose hereinafter described. Thus, it will be observed that when the cutter chain 8 is rotated the cutter bits 9 thereof will operate upon the face as the machine is moved forward, the cutter chain cutting throughout its length.

Operatively connected to the cutter bar, is improved means for moving the same bodily relative to the face as the cutter chain is operated. These means, as shown, include a pair of similarly disposed cranks 11 rigidly connected, as by means of bolts 12, to flanges 13 on the front end of longitudinally disposed shafts 14, 15, journaled in the rigid skeleton and herein rectangular frame 16 of the section 1 and at opposite sides of the center line thereof. As shown, these cranks 11 are driven by a motor 17 of any suitable type, herein a reversible electric motor, controlled by usual controlling means 17' and rigidly supported upon the frame 16 substantially centrally thereof and midway between crank driving shafts 14, 15, the connections as herein-after described preferably being such that the same means serve to drive the cranks and the cutter chain and the latter preferably also serves as a connecting medium driving one crank from the other.

Referring more particularly to Fig. 4, it will be observed that the motor armature shaft 18 carries a pinion 19 meshing with a larger gear 20 journaled in a suitable bearing 21, which in turn meshes with a gear 22 of substantially the same diameter freely rotatable on the shaft 14 at a point in front of the front cross member of the frame 16 and in rear of the flange 13. This gear 22

is in turn rigidly connected, as by a key 23, to a pinion 24 disposed between the same and the flange 13, which in turn meshes with a larger gear 25 keyed at 26 to an inner 5 longitudinally disposed stub shaft 27 journaled in a suitable removable bearing 28 in the end of the left hand crank 11 and rigidly connected, as by bolts 29, to the cutter bar 5. The outer end of this shaft 27 in turn 10 carries a cutter chain driving sprocket 30, and through the cutter chain 8 drives an idler sprocket 31 located at the opposite end of the cutter bar. As shown, this sprocket 31 is in turn fixed to the front 15 end of a stub shaft 32 corresponding to the shaft 27, and similarly journaled in a suitable removable bearing 33 fixed to the cutter bar and itself journaled in the right hand crank 11. Thus it will be noted that rotation 20 of the armature is transmitted to the cutter chain 8.

Operatively connected to this shaft 32 and driven by the rotation thereof as the cutter chain is rotated, is my improved means for 25 rotating the cranks. As shown, the shaft 32 has keyed to its rear end a pinion 34 meshing with a gear 35 carried on the shaft 15 at a point between its flange 13 and the front of the frame. This gear 35 in turn has integrally attached thereto, as by a key 36, a rearwardly disposed pinion 37, which in turn meshes with a gear 38 fixed on the front end of a longitudinally disposed shaft 39 suitably journaled in bearings 40 in the frame 30 and carrying a bevel gear 41 on its rear end rotating in a suitable gear casing 42. This bevel gear 41 in turn meshes constantly with a bevel gear 43 which is disposed between the gear 41 and a cooperating gear 44 rigidly 35 connected to a sleeve 45 journaled at 46 on the frame and in which the shaft 39 is rotatable, the direction of rotation of the sleeve 45 being controlled by a reversing clutch mechanism 47 operable by a suitable 40 controlling member 48 carried on the top of the frame. As shown, this sleeve 45 also carries a pinion 49 thereon meshing with a gear 50 keyed at 51 to the shaft 15 and operating to rotate that shaft and its connected 45 crank 11, while power is transmitted, through the bevel gear 43 and a transverse shaft 52 connected thereto and journaled on the frame, to rotate the other shaft 14 and its connected crank 11. More particularly, 50 it will be observed that the opposite end of the shaft 52 carries a bevel gear 53 meshing with a corresponding bevel gear 54 carried on the rear end of the shaft 55, correspondingly located with respect to the shaft 39 and journaled in suitable bearings 56 on the frame. This shaft 55, however, 55 itself acts as the driving member, the same herein having a pinion 57 keyed thereto and meshing with a gear 58 keyed at 59 to the shaft 14. Thus it will be observed that as

the cutter chain 8 is rotated about the bar 5 the cranks 11 are rotated at a materially slower speed about the axes of the shafts 14, 15 in such a manner as to move the cutter bar in the substantially elliptical path 70 indicated by the cross section of the entry in Fig. 3.

Operatively connected to this crank operating mechanism are improved means for operating the cutter bar in such a manner as 75 to facilitate the removal of obstructions encountered during cutting. These means, as shown, include reversing mechanism preferably automatic and adapted to enable the movement of the cranks to be reversed in 80 such a manner as to oscillate the bar within a variable limited path and thereby enable it to cut away the coal adjacent the obstruction. Referring more particularly to Fig. 4, it will be observed that the shaft 15 is 85 provided with a plurality of cams 61 adjustable angularly and longitudinally relative thereto and adapted to be clamped in adjusted position by means of set screws 62. Normally, these cams are in the inoperative 90 position shown in full lines in Fig. 4. However, when it is desired to oscillate the bar, the cams are adjusted into the dotted line position shown in that figure, so that they may engage at the proper time with the end 95 of a controlling member 63 operatively connected to the reversing clutch 47 and thereby operate that clutch to reverse the direction of movement of the cranks at the desired point. More particularly, it will be 100 observed that by adjusting the cams 61 angularly relative to the shaft and to each other, the cranks may be reversed at any desired time in such a manner as to produce an oscillating movement of any desired 105 length. Here, it will also be noted that since the shaft 15 rotates very slowly, these cams may be adjusted even when the mechanism is in operation, although preferably the motor 110 is shut down during this adjustment.

In my improved construction, the sections 1 and 2 are adapted to be successively advanced along the entry as the latter is extended. As shown, the section 1 is provided with a pair of longitudinally spaced transversely disposed skids 64 rigidly connected to the frame 16 at its opposite ends and sides. Herein the front skid is formed in two arcuate rib and bottom engaging parts disposed on opposite sides of the front end 115 of the conveyor 4, while the rear skid is substantially semi-elliptical in section and provided with a flat bottom resting on the entry bottom, and curved upwardly extending sides engageable with the ribs of the entry. As shown, each of these skids is reinforced transversely by suitable angle irons 64' and the edges of these skids are preferably beveled, as shown at 65, to facilitate movement. In this form of my invention, it will 120

also be noted that the rear or anchoring section 2 is in the form of one of these skids as indicated at 66. This skid is, however, herein provided on each side with an anchoring jack 67 operable by any suitable means, as for instance a hand wheel 68, and movable through a suitable aperture 69 in the skid into engagement with the adjacent side wall or rib of the entry.

10 Operatively connected to the motor and actuated thereby, is the feeding mechanism, which herein operates to feed the sections 1 and 2 forward alternately and at different speeds. As shown, this mechanism includes 15 a plurality of screw shafts 3, rotatable at their front ends in nuts 70, 71 carried by suitable bearings 72 on the rear cross member of the frame 16, and at their rear ends rotatable in nuts 73 carried at the opposite 20 ends of a transversely disposed and horizontal eyener 74 pivotally connected to a forwardly disposed extension 75 on the front end of the rear section 2. Each of these shafts has splined to its front end a recipro- 25 cable clutch member 76 operable by a suitable clutch shipper 77, in turn controlled by a controlling lever 78 carried on the top of the frame, the member 76 having teeth on its opposite ends adapted to engage with 30 cooperating clutch faces 79 and 80 formed on members 81 and 82, of which the members 79 are fixed to the shafts 14 and 15, while the members 80 are freely rotatable on the screw shafts 3 and are connected through 35 chain and sprocket connections 83 with the extending rear ends of the shafts 39 and 55. Thus, it will be observed that by varying the connection of the clutch member 76, the screw shafts 3 may be rotated in opposite 40 directions at different speeds, the same being connected in their slow speed connection, i. e. with the members 81, to feed the cutting mechanism forward during the cutting operation when the rear section 1 is 45 jacked securely in position, and, after a pre-determined forward feeding movement and the release of the jacks 67, then reversibly connected to the members 82, to feed the rear section 2 rapidly toward the section 1, i. e. 50 from the full line position shown in Fig. 2 to the dotted line position shown therein.

55 Operatively associated with the cutting and feeding mechanism hereinabove described, I preferably provide conveyor mechanism adapted to remove the cuttings from the cutting mechanism and convey the same rearwardly where they may be discharged into a car or the like. This conveyor mechanism may, obviously, assume various forms. 60 Herein, it will be noted that the conveyor 4 is provided with an iron-lined middle section and oppositely extending end sections, one of which extends under the frame 16 to a point adjacent the cutting mechanism so that 65 the conveyor may act upon the cuttings on

the front skid 64 and near the cutting mechanism, while the other extends over the rear section 2 so that it may deliver these cuttings into a car if desired. More particularly, it will be observed that the front end of the conveyor is suitably attached, as at 84, to the front skid 64, and that the rear end of the same is slidably supported in suitable upright flange supports 85 on the rear skid 66, preferably at a point above the jacks 67, 70 these supports 85 herein being carried on a transverse lower bracing member 86 herein having formed thereon the lug 75 which in turn carries the pivot 87 for the eyener or crosshead 74.

75 It will also be observed that the conveyor mechanism is herein power driven by suitable means, herein by a separate motor 88 carried on the second skid 64 and operatively connected to the conveyor through a flexible power connection 89. Here attention is also directed to the fact that the mechanism on the section 1 is also preferably enclosed, as by plates 90, and that the controlling members for the several controlling mechanisms are operable from the operator's station at the side of the frame. It will also be noted that the crank driving mechanism disposed in front of the frame is enclosed in suitable gear covers 91.

90 In the operation of my improved construction, it will be noted that as the cutter chain 8 is operated, the cutter bar 5 is moved bodily in opposite directions transversely and vertically through a substantially elliptical path by the cranks 11 and at a speed materially less than the speed of movement of the cutter chain relative to the bar and at the same time that the bar is moved bodily forward by the feeding mechanism. As a result, it will be observed that the cutter chain is enabled to cut progressively throughout its length over the entire surface of the entry face, the face being cut substantially as shown in Figs. 1 and 2. Moreover, it will be 100 noted that an entry of the same configuration as the bar but larger and of the cross section shown in Fig. 3 is thus produced which has the desired strong arched roof, 105 the desired width, and also the desired flat bottom, the entire cut being made in the one operation by the one machine.

110 Obviously, as soon as the section 1 has moved a predetermined distance forward relative to the section 2, by operating the clutch member 76, the slow forward cutting feed of the section 1 may be interrupted and the section 2 fed forward by throwing the members 76 into engagement with the members 82 as soon as the jacks 67 have been released. When the section 2 has thus been brought into the desired position, the clutch may be disconnected and the jacks 67 again adjusted, whereupon the clutch may be reconnected with the members 81 in such a manner as to continue the 115 120 125 130

cutting feed movement of the section 1, this operation being repeated as the entry is extended. It will also be observed that should an obstruction be encountered in the face, 5 such as a sulphur ball or the like, the operator is enabled by adjusting the cams 61 to oscillate the cranks 11 at the same time that the cutter chain is operated and the machine is fed forward, in such a manner as to cause the 10 bar to have a limited oscillatory movement of any desired length at the side or sides of the obstacle and thereby facilitate the removal of the same.

In the use of my improved construction, it 15 will be evident that by varying the shape of the cutter bar the cross section of the entry may be varied within wide limits. It will also be observed that the thrust resulting from engagement of the bits with the face is 20 effectually utilized to assist in the movement of the cranks, the latter being rotated in an opposite direction to the chain, as indicated in Fig. 3, and thereby materially reducing the power required to operate the mechanism. Attention is also directed to the fact that through the provision of the scrapers 10 on the cutter chain the cuttings are forced back from the same and toward the mouth of the conveyor 4 so that the cuttings do not 25 interfere with the operation of the cutter chain and may be readily removed by the conveyor. Due to the provision of my improved operative connections for the sections including the eyener connected feed screw nuts, it 30 will also be observed that the machine may be directed angularly to change the direction of the entry when desired, the feed screws then being adapted to be operated independently in such a manner as to vary the 35 direction of the sections as necessary. These and other advantages of my improved construction will, however, be clearly apparent to those skilled in the art.

While I have in this application specifically described one embodiment which my invention may assume in practice, it is to be understood that this form thereof is used for illustrative purposes only and that the invention may be modified and embodied in 40 various other forms without departing from its spirit or the scope of the appended claims. To avoid possibility of misunderstanding, it is to be understood that allusions to the "face" in the accompanying claims are 45 to the working face, that is to say, the face upon which the cutting operations of the machine are performed.

What I claim as new and desire to secure by Letters Patent is:

60 1. In a mining apparatus, a cutter carrying element disposed substantially parallel to the face, a cutter chain movable thereon, and means for moving said element through a substantially oblong path.

65 2. In a mining apparatus, a cutter carry-

ing element disposed substantially parallel to the face, a cutter chain movable around the periphery thereof, and means for moving said element through a substantially oblong path. 70

3. In a mining apparatus, a cutter carrying element, a cutter chain movable thereon, and means operatively connected to the ends of said element for moving the same through a substantially oblong path. 75

4. In a mining apparatus, a single laterally elongated cutter carrying element disposed substantially parallel to a plane face, and means operatively connected to the ends thereof for moving the same transversely 80 in its plane.

5. In a mining apparatus, a single laterally elongated cutter carrying element disposed substantially parallel to a plane upright face, and means including cranks operatively connected to the ends thereof for moving the same transversely in its plane. 85

6. In a mining apparatus, a cutter carrying element, a cutter chain movable thereon, and means for moving said element through a substantially elliptical path. 90

7. In a mining apparatus, a cutter carrying element, a cutter chain movable thereon, and means operatively connected to the ends of said element for moving the same through a substantially elliptical path. 95

8. In a mining apparatus, a cutter carrying element, a cutter chain movable thereon, and rotating mechanism operatively connected to the ends of said element for moving the same through a substantially elliptical path. 100

9. In a mining apparatus, a substantially elliptical cutter supporting element disposed flatwise against the face, and cutting means including a cutter chain on the surface thereof adjacent the face. 105

10. In a mining apparatus, a substantially elliptical cutter supporting element disposed flatwise against the face, and cutting means including a cutter chain disposed about the periphery of the surface thereof adjacent the face. 110

11. In a mining apparatus, a substantially elliptical cutter supporting element disposed flatwise against a parallel face, and cutting means movable about the periphery of the surface adjacent the face. 115

12. In a mining apparatus, a substantially elliptical cutter supporting element disposed flatwise against the face, and means for moving said element transversely of the face during cutting. 120

13. In a mining apparatus, a substantially elliptical cutter supporting element disposed flatwise against the face, a cutter chain movable on said element and means for moving said element longitudinally and transversely of the face during cutting. 125

14. In a mining apparatus, a cutter sup-

- porting element having a curved upper surface and an oppositely disposed flat bottom surface, and cutting means movable along said surfaces and on the same side of said 5 element.
15. In a mining apparatus, a cutter supporting element having an arcuate edge and an oppositely disposed straight edge, a cutter chain movable on said element, and means 10 for operatively presenting said element flat-wise to a face.
16. In a mining apparatus, a cutter supporting element disposed flat-wise against the face, a cutter chain movable on said 15 element, and means for moving said element relative to the face to cut a larger entry.
17. In a mining apparatus, a cutter supporting element disposed flat-wise against the face, a cutter chain movable thereon 20 and means for moving said element about a plurality of transversely spaced axes.
18. In a mining apparatus, a transversely disposed cutter supporting element disposed substantially parallel to the working face, 25 a cutter chain movable relative thereto, and means for moving said element in a transversely disposed plane during cutting.
19. In a mining apparatus, a transversely disposed cutter supporting element disposed substantially parallel to the working face, 30 a cutter chain movable relative thereto, and means for moving said element both forward and in a transversely disposed plane during cutting.
- 35 20. In a mining apparatus, a cutter carrying element disposed parallel to the face, a movable cutter chain on the working face thereof, and means for operating the same to cut an entry of substantially the same configuration transversely as said cutter carrying element.
21. In a mining apparatus, a cutter carrying element disposed parallel to the face, a 45 movable cutter chain on the working face thereof and means for operating said element to cut an entry of substantially the same configuration as said element but larger than the latter.
- 50 22. In a mining apparatus, an entry cutter carrying element disposed parallel to the face, a movable cutter chain on the working face thereof and means for moving said element bodily vertically and transversely during cutting.
- 55 23. In a mining apparatus, an entry cutter carrying element disposed parallel to the face, a movable cutter chain on the working face thereof and means for moving said element bodily vertically and transversely in 60 opposite directions during cutting.
24. In a mining apparatus, a cutter supporting element disposed parallel to the face, an entry cutting chain thereon, and means utilizing the thrust of the latter for moving 65 said element transversely.
25. In a mining apparatus, a cutter supporting element disposed parallel to the face, an entry cutting chain thereon, and means utilizing the thrust of the latter for moving said element in a substantially elliptical path. 70
26. In a mining apparatus, a cutter supporting element disposed parallel to a face, a cutter chain movable thereon, and rotating means for moving said element transversely in an opposite direction to said chain. 75
27. In a mining apparatus, a substantially elliptical cutter carrying element disposed parallel to the face, cutters thereon including a movable cutter chain and means for simultaneously actuating the cutters thereon and moving said element transversely of the face. 80
28. In a mining apparatus, a substantially elliptical cutter carrying element disposed substantially flat against the face, cutters thereon including a movable cutter chain thereon and means for simultaneously moving said element transversely and feeding it toward the face. 85
29. In a mining apparatus, a substantially vertically disposed cutter carrying element, 90 a cutter chain movable thereon, crank mechanism operatively connected with the opposite ends thereof, and means for feeding said mechanism toward the work.
30. In a mining apparatus, a substantially vertically disposed cutter carrying element, 95 crank mechanism operatively connected with the opposite ends thereof, and means for reversing the crank movement.
31. In a mining apparatus, a substantially vertically disposed cutter carrying element, 100 crank mechanism operatively connected with the opposite ends thereof, and automatically acting means for reversing the crank movement. 105
32. In a mining apparatus, a substantially vertically disposed cutter carrying element, 110 crank mechanism operatively connected with the opposite ends thereof, and adjustable automatically acting means for reversing the crank movement.
33. In a mining apparatus, a substantially vertically disposed cutter carrying element, 115 crank mechanism operatively connected with the opposite ends thereof, and means for selectively rotating or oscillating said crank mechanism.
34. In a mining apparatus, a substantially vertically disposed cutter carrying element, 120 crank mechanism operatively connected with the opposite ends thereof, and means for selectively rotating or oscillating said crank mechanism through variable amplitudes.
35. In a mining apparatus, a cutter supporting element, a cutter chain thereon, and means operatively connected by said chain for moving the same transversely during cutting. 125
36. In a mining apparatus, a cutter supporting element, a cutter chain thereon, and 130

crank mechanism operatively connected by said chain for moving said element transversely during cutting.

37. In a mining apparatus, a cutter carrying section, an anchoring section, feed-screws thereon, an evener pivotally mounted on said second section, and feed screw nuts carried on said evener.

38. In a mining apparatus, a cutter carrying section, an operatively connected anchoring section, and a substantially semi-elliptical transverse skid disposed under and at the sides of each of said sections.

39. In a mining apparatus, a frame, a cutter bar disposed transversely thereof, a cutter chain thereon, cranks operatively connected to the ends of said bar, a motor, and operative connections thereto for rotating said cranks and cutter chain.

40. In a mining apparatus, a frame, a cutter bar thereon, cranks operatively connected to the ends thereof, a motor, and operative connections between the same and said cranks including a cutter chain operatively connecting said cranks.

41. In a mining apparatus, a frame, a cutter bar thereon, cranks operatively connected to the ends thereof, a cutter chain operatively connecting said cranks, and means for rotating said cranks and chain at different speeds.

42. In a mining apparatus, a frame, a cutter bar thereon, cranks operatively connected to the ends thereof, a cutter chain operatively connecting said cranks, and means for rotating said cranks and chain in opposite directions.

43. In a mining apparatus, a frame, a cutter bar thereon, cranks operatively connected to the ends thereof, a cutter chain operatively connecting said cranks, and means for rotating said cranks and chain in opposite directions at different speeds.

44. In a mining apparatus, a cutter carrying element, cranks operatively connected to the opposite ends thereof, a cutter chain operatively connecting said cranks, and means for oscillating said cranks while continuously rotating said chain.

45. In a mining apparatus, a cutter carrying element, cranks operatively connected to the opposite ends thereof, a cutter chain operatively connecting said cranks, means for oscillating said cranks through paths of variable amplitude while continuously rotating said chain and feeding the latter toward the work.

46. In a mining apparatus, a plurality of

sections, mechanism for feeding either relative to the other, cutting mechanism carried on one of said sections and disposed in a plane substantially parallel to the face, and driving mechanism carried on said section operatively connectable with said cutting mechanism and said feeding mechanism. 65

47. In a mining apparatus, a cutter carrying element disposed parallel to the face, driving mechanism, and operative connections therewith for moving said element through a substantially elliptical path and simultaneously moving said element toward the face. 70

48. In a mining apparatus, an upright cutter bar disposed flatwise to a parallel face, a cutter chain thereon, driving mechanism, and operative connections therewith for operating said cutter chain at one speed and for feeding said bar forward at another speed. 75

49. In a mining apparatus, a cutter bar 80 disposed parallel to the face, a cutter chain thereon, driving mechanism, and operative connections therewith for moving said bar slowly through a substantially elliptical path, operating said cutter chain, and moving said bar forward. 85

50. In a mining apparatus, a cutter carrying section, an anchoring section, a cutter bar on said carrying section, a cutter chain on said bar, feeding mechanism between 90 said sections, driving mechanism on said cutter carrying section, and means operatively connectable therewith for moving said bar through a substantially elliptical path in a plane parallel to the face, operating 95 said cutter chain, moving said bar forward, and moving said sections one relative to the other.

51. In a mining apparatus, a single plane cutter carrying element having cutters movable about its outer edge, said element being disposed substantially parallel to a plane face, and means operatively connected to said element for orbitally moving the same to cut out a substantially larger oblong opening. 100

52. In a mining apparatus, a single laterally elongated plane cutter carrying element having cutters movable about its outer edge, said element being disposed substantially parallel to a plane face, and means operatively connected to said element for orbitally moving the same transversely in its plane. 110

In testimony whereof I affix my signature.
MORRIS P. HOLMES.

CERTIFICATE OF CORRECTION.

Patent No. 1,645,003.

Granted October 11, 1927, to

MORRIS P. HOLMES.

It is hereby certified that error appears in the printed specification of the above numbered patent requiring correction as follows: Page 4, line 89, claim 6, after the word "element" insert the words "disposed substantially parallel to the face"; same page, line 127, claim 13, after the word "element" insert a comma; page 5, line 19, claim 17, after the word "thereon" insert a comma; same page, lines 45, 52 and 58, claims 21, 22 and 23, after the word "thereof" and in line 79, claim 27, after the word "chain" and line 86, claim 28, after the word "thereon" insert a comma; page 5, lines 38 to 41, strike out the words "the same to cut an entry of substantially the same configuration transversely as said cutter carrying element" and insert instead "said element to cut an entry of substantially the same configuration transversely as said cutter carrying element"; and that the said Letters Patent should be read with these corrections therein that the same may conform to the record of the case in the Patent Office.

Signed and sealed this 20th day of December, A. D. 1927.

Seal.

M. J. Moore,
Acting Commissioner of Patents.
